CATCH BASIN FILLER

John R. Ehmke, 6612 Champana,
Florissant, Mo. 63033

Filed July 10, 1972, Ser. No. 269,959

Term of patent 14 years

Int. Cl. D23—01

U.S. Cl. D23—1

Fig. 1

Fig. 2

Fig. 3

FIG. 1 is a side elevational view of a catch basin filler showing my new design;

FIG. 2 is a vertical center cross sectional view thereof; and

FIG. 3 is a top plan view thereof.

I claim:

The ornamental design for a catch basin filler, as shown.
